UNITED STATES PATENT OFFICE

WILLIAM A. FRENCH, OF MINNEAPOLIS, MINNESOTA, ASSIGNOR TO WM. A. FRENCH
FURNITURE CO., OF MINNEAPOLIS, MINNESOTA

DESIGN FOR A BEDSTEAD FRAME

Application filed April 3, 1929. Serial No. 30,737. Term of patent 3½ years.

To all whom it may concern:

Be it known that I, WILLIAM A. FRENCH, a citizen of the United States, residing at Minneapolis, in the county of Hennepin and State of Minnesota, have invented a new, original, and ornamental Design for Bedstead Frame, of which the following is a specification, reference being had to the accompanying drawing, forming part thereof.

Fig. 1 is a perspective view of a bedstead frame, showing my new design.

Fig. 2 is an enlarged elevational view of one of the corner posts.

I claim:

The ornamental design for a bedstead frame, as shown.

In testimony whereof I hereunto affix my signature.

WILLIAM A. FRENCH.
